UNITED STATES PATENT OFFICE.

JAMES ADAIR, OF ALEPO TOWNSHIP, (PITTSBURG P. O.,) ALLEGHENY COUNTY, PENNSYLVANIA.

FIRE-PLACE.

SPECIFICATION forming part of Letters Patent No. 230,390, dated July 27, 1880.

Application filed October 3, 1879.

To all whom it may concern:

Be it known that I, JAMES ADAIR, of Alepo Township, (Pittsburg P. O.,) county of Allegheny, State of Pennsylvania, have invented 5 or discovered a new and useful Improvement in Fire-Places; and I do hereby declare the following to be a full, clear, concise, and exact description thereof, reference being had to the accompanying drawings, making a part of this 10 specification, in which—like letters indicating like parts—

Figure 1, Sheet 1, is a perspective view of my improved fire-place and grate arranged for use. Fig. 2 is a similar view, illustrative of the manner of adjusting the grate for summer, the front being broken away in part, the better to show the interior. Fig. 3 is a vertical central section through the fire-place and grate, showing, in perspective, the parts arranged in the 20 same manner or relation as in Fig. 1, but drawn to an enlarged scale. Figs. 4 and 5 are detached perspective views on the scale of Fig. 3, illustrating separate parts of the grate proper. Fig. 6, Sheet 2, is a front elevation 25 of my improvement, showing the summer front and ash-screen in place. Fig. 7 is a vertical sectional view through the fire-place and grate-front, the grate proper being removed; and Figs. 8, 9, and 10 are views 30 illustrative of the manner of forming the grate-front. Figs. 11, 12, and 13, Sheet 3, are detached perspective views of parts of the grate, 35 illustrative of modifications in construction, as hereinafter described.

The scale of the figures on Sheet 2 is intermediate between those of Figs. 1 and 3, Sheet 1.

My invention relates to certain improvements in fire-places and grates; and it consists in forming the several parts and arranging and combining them, as hereinafter described and claimed.

In the drawings, A represents the fire-place, which is lined with side tile, B B, back tile, D D', and roof-tile C.

It has been customary heretofore to incline 45 the roof-tile of a fire-place upward toward the front. Such arrangement is objectional, because the upward slope of its under face wastefully hastens the escape of the hot gases and 50 smoke from the fire-place, and also a large

space is thereby formed in rear of and above such tile, which accumulates soot and causes eddies or swirls in the ascending smoke, unless such space is filled with masonry; but such filling is very difficult to remove in case 55 it is necessary, for any cause, as frequently occurs, to reset or readjust the roof-tile.

I overcome these difficulties by sloping the roof-tile C downward toward the front of the grate, and thereby form a slight recess under 60 the tile, which will tend to retard the escape from the fire-place of the heated gases, and to cause their combustion to be made more complete, while the smooth incline along the upper side of the tile, which is nearly in the direct and natural line of draft, will facilitate the escape of the spent gases up the flue after 65 they have once passed the front edge of the tile. Thus by the adjustment of this tile I improve or increase the combustion in the fire-place, and at the same time, without extra back filling, I prevent the tendency to puff smoke into the room, which exists when an air-chamber is formed back of and above the tile. I 70 also perforate this tile with a number of small 75 holes, c, or otherwise form equivalent passages through the same, which serve as flame and air passages and promote combustion of the escaping gases above, as well as below, the tile, especially if the well-known or any suitable rear 80 dust-flue be arranged to discharge its air immediately below the roof-tile. The tile being thus heated on both sides will become very hot, unsightly soot or carbon, which might otherwise 85 collect upon it, will be burned, and owing to its exposed position a great deal of heat will be radiated from it into the room. This tile C may 90 rest upon the end and back tile, and all may be supported and secured in any convenient way.

Instead of making the lower back tile, D, plain and uniform in thickness, or, on the other hand, weakening it by flutings or gutters, as has heretofore been practiced, I add to its lower front face a series of triangular projections, d, 95 having their bases downward and their front edges receding or sloping upward and backward to or toward the face of the tile. Spaces d' are left between these projections, by preference about equal to the spaces usually made 100

between grate-bars. These spaces may have vertical or tapering sides, as preferred, and they serve as air-passages to supply air from below to the back of the fire, and thence up 5 the tile D D' to the roof-tile C. They also serve to cover, in part, the bottom of the fire-basket, and thus diminish the requisite extent of the grate-bars, and especially they prevent the accumulation of ashes upon the back tile.

10 The attainment of these objects or advantages is very desirable, and I fully secure them, to a practical extent, by forming the tile D as described, and at the same time I make the important provision for a clear space for agitating the grate-bars, as hereinafter described.

15 The end tile, B B, may have either plane faces, as shown, or projections may be made along their lower edges, as described with reference to tile D, which will serve, in such 20 construction, most of the advantages above named.

The grate proper is formed in two parts or members, E and F. (Shown in detached views, Figs. 4 and 5.) The part E is composed of ribs 25 or bars e, projecting at suitable intervals from the main or spinal shaft e', to which they are by preference cast. A handle or a pair of operating-shafts, h, extend back from the ends of the spinal shaft e' and rest on the cross-bar S of the grate-front, at which place they are, by preference, bent downward somewhat, so as to project out from the front a little way 30 in a horizontal or nearly horizontal direction. I have shown this handle h rigidly attached 35 to its grate E. It may be made detachable, however, if preferred—as, for example, by a pin, socket, and set-screw connection located at or near the grate-front—and the handle may be made solid or tubular and of any suitable 40 form and material. This part, E, of the grate is detachably pivoted to a rod, i, which is secured in the side walls of the fire-place in the desired position.

The pivot seats or bearings are formed by 45 spurs or equivalent hooks or lugs i', projecting from the under side of E. Open-sided bearings or forks are thus secured, which not only permit the grate to be rocked or turned on the rod i, but also allow of a sliding movement 50 into and out of the fire-place, as hereinafter described, and in so doing the bars e will rest and slide upon the rod i.

If preferred, the pivotal fork i' may be made by two or more ribs, i², Fig. 11, Sheet 3, projecting from the under side of the spinal shaft e', arranged intermediate between the ribs e.

The other part or member, F, of the grate is formed of a fore plate, f', which covers the space between the top edge of cross-bar S and 60 spinal shaft e', and comb-teeth or bars f project from the inner edge of this plate f', which teeth are arranged to lie between and alternate with the bars e. These two parts E and F of the grate are detachably pivoted together by 65 means of open-sided sockets or forks on the under side of F, formed by the bent lugs or

hooks g, which clasp the spinal shaft e', preferably at or near either end. The part F may thus have independent motion upon its pivot and into and out of the fire-place, the same as 70 the part E upon the rod i; or the two parts may have joint and combined motion upon these pivots at the same time, as presently described.

Stops or lugs g', near the center of the spinal shaft e', bear upon either side of one of the bars f, and not only guide the part F into proper position, but also prevent displacement of the same when the grate is agitated. As thus arranged the greater part of the weight 80 of F will be supported by the spinal shaft e', and the combined weight of both E and F is supported by the rod i and cross-bar S. The position of this cross-bar with relation to the rod i is, by preference, such as to give considerable downward incline to the grate, as shown, and secure the desired depth of fire-basket at the rear; and the adjustment between the two parts E and F is such that their upper surfaces are in the same or nearly the same plane. 90

The fore plate, f', is by preference pierced or perforated with a number of holes, k, for supplying air in limited quantities to the front of the fire, though I prefer to introduce the greater part of the air at the back, and I provide for 95 this, in the construction of the grate, by the use of the fore plate, f', in front and the bars e and f and passages d' in the rear.

In case the fore plate, f', should become covered with ashes, or coked coal should adhere 100 thereto, it may be cleared by running a rod or poker, l, through holes m' in the flange or rim m, and vibrating its end over the surface of the plate, as shown in dotted lines, Fig. 3.

The flange or rim m on the front edge of fore 105 plate, f', is designed to prevent coals and ashes from dropping over the front of the fire-basket. But, as an additional precaution in this respect, and also as a means of operating the part F of the grate, I clip or otherwise rigidly attach to 110 this flange m a balcony or fender plate, H, which is so placed, by preference, as to be bounded by the operating shaft or handle h.

If desired, this fender, as well as the handle h, may be plated and otherwise ornamented, 115 and the floor of the fender may be laid with Minton tile, so as to give it an attractive appearance.

By raising the fender H with the foot, poker, or hand the part F will be tilted on its pivot 120 without disturbing the part E, and the front of the fire will be effectually agitated or stirred. In order, however, to agitate both parts of the grate at once, I make use of the operating handle or shaft h, either by grasping it with 125 the hand or by passing the poker l through holes h' and m', as in full lines, Fig. 3; then by raising and lowering this handle the part E will be turned on its pivot-rod i, and the points of the bars e be given a vibratory motion corresponding to that of the handle; at 130 the same time the spine e' on the under side of

the part F will vibrate the bars f, the front edge of the fore plate, f', rocking on the cross-bar S. The two vibrating sets of bars e and f will thus be given a shearing motion past each other, and the whole contents of the fire-basket will be effectually stirred and cleared of ashes, &c. This same shear motion of the grate-bars may be secured by extending the heel or stub of one of the bars e—as, for example, the middle one—as shown in dotted lines at e⁵, Fig. 11, back under the fore plate, f', a sufficient distance to impart to such plate the desired motion as the grate E is rocked on its pivot, and in such construction the pivots i and g may be 15 in the same, or nearly the same, vertical plane.

By raising the handle h and fender H together both parts of the grate will be turned on the rod i, and the entire contents of the fire-basket be discharged or dumped into the 20 ash-receiver R'; or, if preferred, the grate may be given a sliding motion into and out of the fire-basket, which may be made to discharge the contents of the basket. This sliding motion may be either in the plane of the position 25 of the grate when at rest, or the sliding motion may be combined with the tilting motion on the rod i, and this combined motion will be found particularly advantageous where the ash-receiver R' is shallow, as by means of it the 30 grate can be brought back to place without disturbing the discharged ashes.

When it is desired to close the grate for summer the parts E and F, with their attachments, may be turned or folded on rod i against the back of the fire-place, as illustrated in Fig. 2. The fire-place may then be closed with a summer-front, O, as in Fig. 6.

The center of motion of the part F of the grate, when E and F are both agitated, is along 40 the cross-bar S. This being considerably higher than the points of the bars f, the line of motion of these points, as the grate is agitated, will be upward and backward, and by sloping the front edges of the tile-projections 45 d, as described, there is no danger of striking them with the ends of these bars, which would be the case were the face of the tile vertical and the bars were extended near to such face; also, the fuel in the fire-basket is easily raised along 50 such slope, with little or no danger of coal or cinders wedging in between the tile and the ends of the bars. The angle between the sloping edge of projections d and the face of the grate when in position is, by preference, about 55 ninety degrees.

If desired, the bars f, or some of them, may project a little ways into the passages d', so as to assist in clearing them of ashes, though I do not consider this essential; also, the ribs e 60 may be extended across the spine e', and closely or loosely enter corresponding slots or recesses cut into the adjacent edge of the fore plate, f', as at e⁴, Fig. 11; but I prefer the construction shown, as less metal is required in its construction, there is less danger of clinkers interfering with the motion of the ribs, the bar S is

better protected from the heat of the fire, and air is better directed to the rear part of the fire-basket.

The parts E and F of the grate may be pivoted at any desired point inside the grate-front, so as to have a shear motion with relation to each other, as described. I prefer, however, to locate the pivot-rod i near the transverse center of the fire-basket, as the leverage secured thereby upon the parts E and F renders their agitation and operation an easy matter; and this I claim as one great advantage in my invention, that the operation of the grate is made not only so convenient, but also 80 so easy that it is practically within the strength and ability of a child or of the infirm, and at the same time it is safe and well guarded from danger of accident.

By placing the pivoting-rod i nearer the 85 front more motion might be given the bars e and f for a given motion of the handle h; but in such case more strength would be required.

The pivots between the parts E and F and rod i may be near the center of such parts instead of near the ends, as shown.

It will also be observed that a slight modification of F, Fig. 4, would enable one such member to be mounted over another almost similar member, as illustrated by detached 95 view, Fig. 13, the two forming what may be described as a very large wide pair of flat pinchers or tongs with forked jaws, the fore plate and fender-plate of each constituting a handle. Separating these so-called handles 100 would cause the forked jaws to separate, thereby agitating the fuel.

It may also be mentioned that the central part of the fore plate, f³, Fig. 12, bounded on the upper side by the flange and on the lower 105 side by the lower range of holes, may be cut away and attached to a rear rib, e⁶, carried on the spine-shaft. In such case this cut away part of the fore plate would rise and fall as the handle is operated.

It will also occur to the skilled in the art that the flange m and the rod h may have a permanent coupling-bar, q, between them provided with a vertical socket or poker-hole, q', by which to operate it.

These and other like modifications I consider as coming within my invention.

Another part of my invention relates to certain improvements in the form and construction of the grate-front N, whereby I both adapt 120 it to the construction of grate described and also increase its utility and cheapness.

In making this front, I take a sheet of polished Bessemer steel of proper size, and while properly heated, by the use of suitable rolls, 125 dies, or a drop, I form therein V-shaped crimps or grooves o o along the boundary-lines of the outside edge, the front opening to the fire-basket and of the ash-screen opening, as illustrated in Figs. 8 and 9, Sheet 2. These crimps 130 or grooves are made by stretching the metal, which, when hot, is very plastic.

By grinding or cutting through the apices of these crimps I remove or sever the pieces O and R, and also the outside rim or waste, W, and secure inwardly-bent flanges *r r* on the front N and pieces O and R corresponding to the crimps first formed. The flanges *r r* are then pressed with dies or otherwise fitted into the desired square-cornered form, and worked outward until the pieces O and R properly fill the openings from which they were respectively taken. They thus form doors to close such openings, O serving as a summer-front and R as the ash-screen front or door, through which scrolls or holes *u* should be cut to supply air to the under side of the fire.

The flanges *r r* serve a useful purpose in holding the doors R and O in place. They also give the edges a smooth finish and the whole front additional strength. Moreover, between the flanges on the edges of the cross-bar S, I place suitable fire-proof tile *s*, or glass, or equivalent material, which may be colored and ornamented as desired, and holes or openings *s'* through the cross-bar will expose such ornamentation, as illustrated in Fig. 6, Sheet 2, and thus add very much to the beauty of the grate-front. The principal reasons, however, for using tile or its equivalent along the back of S are to give it strength to support the grates E F, as described, and to protect it from being warped or burned by the heat of the fire. The fore plate, *f'*, also assists in this latter object, as it arrests the heat of the fire much better than the usual open-grate bars would do.

Upon removing the door R the ashes under the grate-bars may be taken up in the usual way, or they may be passed to a pit or box in the cellar, as preferred.

The front N may be secured in place in any convenient way.

In patent granted to me July 4, 1876, No. 179,389, I have shown a fender-plate hinged to a low-down grate; but such arrangement would not serve the purpose which I here secure by rigidly attaching the fender H to flange *m*.

In general terms, my present invention may be said to be an improvement in the class of grates shown in aforesaid patent, and also in patents granted to me July 6, 1875, No. 165,194, and June 19, 1877, No. 192,046.

Some of the advantages which I secure in my present invention over the construction shown in these patents and others of the same class are, that I dispense with the supporting-frame around the grate-bars, and thus add to the simplicity and cheapness of the grate, and avoid the loading of ashes upon such frame.

I also secure better dumping facilities and a better shaking or agitating motion—one that can be operated without any specially-formed tool and with utmost ease and safety. I secure a better draft, better combustion above and under the roof-tile, and consequently better radiation of heat, a much better grate-front,

and better protection for the transverse bar of the same, and, especially, I secure a much more simple, and consequently a much better grate, than any of which I have heretofore had 70 knowledge.

By the term "fire-place," as used herein, I include open-grate stoves and other devices for generating heat involving a similar function and construction to the fire-place described.

I am aware that, broadly considered, it is not new to pivot a fire-place grate in such way that it may be turned upon its pivots into the fire-place, and therefore I limit myself in this 80 respect to the combination of devices involved in this operation, substantially as herein set forth and hereinafter claimed; neither do I claim herein the grate-front described, by itself considered, nor the method described of making the same, such matter forming the subject of another application.

I claim herein as my invention—

1. In a fire-place, the combination of a forwardly-depressed perforated roof-tile, C, rear tile, D, having air-passages *d'* and triangular projections *d*, and a suitable grate for forming a fire-basket under such roof-tile and in front of the rear tile, substantially as set forth.

2. In a fire-basket, the combination of rear tile, D, having projections *d* and intermediate passages *d'* on its lower front edge, with end tile, B B, and grate-bars forming the front and bottom of the basket, substantially as set forth.

3. In a fire-place, and in combination therewith, a pivoted two-part grate having an operating-shaft and fender attached thereto, which are arranged to project somewhat in front of the grate and adapted to be turned 105 with the grate on its pivot into the interior of the fire-place, substantially as and for the purposes set forth.

4. The combination of pivot-rod *i*, grate E, pivoted thereto or adapted to turn thereon, 110 grate F, pivoted on the grate E, and rest or front cross-bar, S, arranged substantially as described.

5. The combination of grates E and F, pivoted to each other and arranged with alternating bars or teeth *e* and *f*, rest-bar S, operating-shaft *h*, fender H, and rod *i*, substantially as set forth.

6. The combination of a pivoted grate-bar and a fender-plate rigidly secured to the front 120 of such grate-bar, substantially as set forth, whereby such plate serves as a means for agitating and dumping the grate and as a fender when the grate is in position.

7. The combination of a low-down fire-place 125 grate, transverse bar S, in front of such grate, and tile *s*, arranged against the rear face of the bar, to protect, strengthen, and ornament the same, substantially as set forth.

8. A metal fire-place front, N, having a 130 transverse bar, S, integral therewith, and having a fire-basket opening above such bar and

an ash screen or receiver opening below such bar, in combination with a fire-grate supported at its front edge upon such transverse bar, substantially as set forth.

- 5 9. The combination of grate E, having bars e, spinal shaft e', and lugs g', grate F, having bars f, and fore plate, f', supporting or cross bar S, and pivot-rod i, arranged substantially as and for the purposes described.
- 10 10. In the fire-basket of a fire-place, and in combination therewith, a wall-tile arranged in a vertical or nearly vertical position and hav-

ing at its lower front edge a succession of projections, d, and intermediate passages, substantially as described, whereby a succession of 15 sloping edges are formed across the lower corner of the fire-basket.

In testimony whereof I have hereunto set my hand.

JAMES ADAIR.
